CLOSURE CAP AND METHOD OF MAKING SAME
Daniel D. Acton and Alexander W. Hart, Lancaster, Ohio,
assignors to Anchor Hocking Glass Corporation, Lancaster, Ohio, a corporation of Delaware

Filed Oct. 14, 1963, Ser. No. 315,805
7 Claims. (Cl. 215—38)

The present invention relates to the sealing art and more particularly to an improved closure cap and an improved method of making a closure cap.

Closure caps are usually formed by stamping a cup-shaped shell out of a sheet of metal and thereafter passing the shell through a series of shaping tools to form the finished closure cap. In order to form all the structural features of a finished closure cap it has been found that a large amount of metal is used.

The present invention has for one of its objects the provision of an improved method of making a closure cap in which the amount of material used to form the closure cap is reduced substantially.

Another object of the present invention is the provision of an improved closure cap.

Another object of the present invention is the provision of an improved press-on closure cap.

Another object of the present invention is the provision of an improved non-circular closure cap.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

FIG. 1 is a perspective view partly in section showing a closure cap made in accordance with the present invention;

FIG. 2 is a perspective view of a blank from which the closure cap is formed;

FIG. 3 is a perspective view showing the blank of FIG. 2 formed into a cup-shaped shell;

FIG. 4 is a sectional view taken along line 4—4 of FIG. 3;

FIG. 5 is a perspective view showing the step of coaxing the skirt of the cup-shaped shell inwardly;

FIG. 6 is a sectional view taken along line 6—6 of FIG. 5;

FIG. 7 is a perspective view showing a further step in the formation of the closure cap;

FIG. 8 is a sectional view taken along line 8—8 of FIG. 7;

FIG. 9 is a sectional view of the finished closure cap taken along line 9—9 of FIG. 1 and showing the position of the closure cap when applied to a container;

FIG. 10 is a perspective view of a non-circular closure cap which may be made in accordance with the present invention;

FIG. 11 is a side elevational view thereof;

FIG. 12 is a plan view of a blank from which the closure cap is made;

FIG. 13 is a perspective view showing a shell made from the blank of FIG. 12;

FIG. 14 is a side elevational view of the shell shown in FIG. 13;

FIG. 15 is a sectional view taken along line 15—15 of FIG. 14;

FIG. 16 is a sectional view showing the initial step of coaxing the edge of the skirt portion inwardly;

2

FIG. 17 is a sectional view showing another step in the formation of the closure cap;

FIG. 18 is a bottom plan view of the completed closure;

FIG. 19 is a sectional view taken along line 19—19 of FIG. 18; and

FIG. 20 is a sectional view taken along line 20—20 of FIG. 18.

For simplicity the invention will be described in connection with a so-called "press-on" type closure cap, i.e., a closure cap that is applied to a container by pressing down on it without applying a torque. However, it will be understood that the present invention may also be used in connection with other types of caps, such as twist-caps, etc.

Referring to the drawings, and particularly to the embodiment of the invention shown in FIGS. 1 to 9, the closure cap 1 of the present invention comprises a cover portion 2 and a skirt portion 3. A depressed annular bead 4 is provided in the cover portion to form a gasket receiving channel 5 between the bead 4 and the skirt portion 3. The gasket-receiving channel 5 is adapted to receive a sealing gasket 6 therein which, in the embodiment shown in the drawing, is a so-called "flowed-in" type of gasket, i.e., a gasket which is formed by flowing a material in a plastic state into the channel 5 and which then sets to form the finished gasket 6. However, it will be understood that other types of sealing elements, such as cut gaskets or pulp type sealing liners, may also be used, if desired and it will be further understood that the present invention may also be used in connection with a closure cap which does not have a gasket-receiving channel.

The skirt portion 3 has its lower edge rolled inwardly to form a bead 7. The bead 7 is provided with a plurality of spaced holding lugs 8 which extend inwardly and upwardly from the bead 7. Each lug 8 has an upwardly extending inner wall 9 spaced from the skirt portion 3 and an upper curved holding portion 10 extending inwardly toward the inner surface of the skirt portion 3 and downwardly toward the lower edge of the bead.

The closure cap 1 is adapted to be snapped on to a container 20. In the embodiment shown in the drawings the container 20 has an upper rim 21 which cooperates with the sealing gasket 6 of the closure cap 1 to form an hermetic seal. The container 20 is also provided with an outwardly extending holding bead 22 adapted to cooperate with the curved holding portion 10 of the holding lugs 8 of the closure cap 1 to hold the closure cap 1 in place.

In operation, the closure cap 1 is pressed down over the container 20 until the holding portion 10 snaps under the holding bead 22 and the sealing gasket 6 presses on the rim 21. While for convenience, the present invention is being described with particular reference to a container with a holding bead 22 as shown in the drawing, it will be understood that the structure of the container may be changed, if desired.

The closure cap 1 is formed from a blank 12 which is shown in FIG. 2. The blank 12 has a polygonal shape having a plurality of side edges 13 connecting apexes 14 together. In the embodiment of the invention shown in drawings the blank 12 is hexagonal, however, it will be understood that other configurations may be used.

The blank 12 is preferably stamped from a sheet of metal (not shown), however, it will be understood that the blank 12 may be formed in any desired manner.

The blank 12 is first formed into a cup-shaped shell 15 (FIGS. 3 and 4) with cover portion 2, depressed bead 4 and skirt portion 3. It will be noted that when the blank 12 is drawn to form the shell 15 the edges 13 assume a curved configuration and the apexes 14 extend

below the edges 13 to give the skirt 3 of the shell 15 a generally undulating appearance.

The apexes 14 are next coaxed inwardly as shown in FIGS. 5 and 6. The whole skirt 3 is then curled inwardly and upwardly at a point above the edges 13, as shown in FIGS. 7 and 8, to form the lugs 8. With this curling operation the edges 13 are rolled inwardly to form the bead 7 and the apexes 14 are moved to the position as shown in FIG. 9, to form the upper portion 10 of the lug 9.

It will thus be seen that by using the apexes 14 of the blank 12 to form the lugs 8, the closure cap is formed with a minimum of material and with fewer steps than heretofore possible.

It will also be seen that by using a hexagonal blank 12 a closure cap with six holding lugs 8 is formed, since each apex 14 becomes a lug. Thus, if a closure cap with a different number of lugs is desired, a blank of different geometrical configuration may be used. Hence, a triangular blank would be used to form a three lug cap, a rectangular blank would be used to form a four lug cap, etc.

Furthermore, the flattened-out length of each lug is greater than the flattened-out length of the skirt and the bead.

It will also be seen what while the construction of the lugs 8 is shown in the drawing as particularly adapted for a press-on cap, the present invention can also be used to make closure caps with other types of lugs.

FIGS. 10 to 20 show another embodiment of the present invention in which a non-circular cap 30 is formed. The cap 30 is shown as having a rectangular configuration and is provided with a cover portion 31 having shoulders 30 adapted to form a gasket-receiving channel 51 and a skirt portion 32 depending from the cover portion 31. Since closure cap 30 is rectangular the cover portion 31 is rectangular and the skirt portion 32 is formed in sections 33 and 34 at right angles to each other and joined to each other at corners 35.

The lower edge of the skirt portion 32 is rolled inwardly to form a bead 36. Holding lugs 37 and 38 extend inwardly from the bead 36 in spaced relation to each other. The lugs 37 are integral with and extend from skirt section 33 and lugs 38 are integral with and extend from skirt section 34.

The lugs 37 and 38 are similar in construction to the lugs 8 shown in the embodiment of FIGS. 1 to 9. Lugs 37 and 38 have a wall portion 39 and 40 respectively, extending upwardly and spaced from the skirt sections 33 and 34, respectively, and upper curved portion 41 and 42 extending inwardly toward skirt portions 33 and 34, respectively.

The cap is formed from an oval blank 44 shown in FIG. 12. The oval blank 44 has arcs 45 in the direction of its major axis and arcs 46 in the direction of its minor axis. The blank is drawn along chords 47 and 48, opposite arcs 45 and 46, respectively, into a rectangularly shaped shell 49, as shown in FIGS. 13 and 14.

The shell 49 is formed with cover portion 31, gasket-receiving channel 51 and skirt sections 33 and 34. It will be noted that the arcs 45 and 46 of the blank 44 become the lower edges of the skirt sections 33 and 34, respectively, when the shell 49 is formed.

The edges 45 are then coaxed inwardly, as shown in FIG. 16, and the skirt sections 33 and 34 are then curled inwardly and upwardly, as shown in FIG. 17, to form the lugs 37 and 38, respectively.

A liner 55 may then be inserted into the closure cap or, if desired, a gasket (not shown) may be inserted in a gasket-receiving channel 51.

It will be understood that although closure cap 30 is illustrated in the drawings as having the lugs with a particular configuration, the configuration of the lugs may be changed without departing from the scope of the invention.

The present invention may also be used to make an oval shaped closure cap from a polygonal blank.

As an example, a blank may be used which differs from the equilateral hexagonal blank shown in the drawings in that two of its opposite sides are elongated. The extent of elongation of the size of the blank will be determined by the desired shape of the finished oval closure cap. The finished oval cap is then formed in a manner similar to that used in connection with the formation of a round cap, as described above.

It will also be noted that although for convenience, the drawings illustrate the invention by showing a rectangular closure cap 30 formed from an oval blank 44, it is within the purview of the present invention to form other non-circular closure caps from generally circular blanks. Thus square cap may be formed from a circular blank or polygonal cap may be formed from a circular blank by merely drawing the blank along different chords with the segment of the blank between the chord and the arc which it faces being used to form the lug construction.

Here again the flattened-out length of each lug is greater than the flattened-out length of the bead and the skirt.

Hence, it will be seen that the present invention provides an improved method of making a closure cap either circular or non-circular and an improved closure cap made thereby in which no excess material is used.

It will further be seen that the present invention enables a much deeper cap to be formed and gives a choice for location of the lugs because of the absence of material at the edges of the skirt. Furthermore, the absence of such material also increases the flexibility of the skirt portion.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described the invention, it is claimed:

1. A closure cap comprising a cover portion and a skirt portion, the edge of the skirt portion being rolled inwardly to form a bead, elongated lugs extending inwardly from said skirt portion and integral with said bead, the lower edge of the bead and of said lugs being on substantially the same plane, the flattened-out length of each lug being greater than the flattened-out length of said skirt portion.

2. A closure cap comprising a cover portion and a skirt portion, lugs extending inwardly from said skirt portion, said lugs comprising an upwardly extending wall elongated in a substantially vertical direction and spaced inwardly from said skirt portion and a holding portion above said wall, the flattened-out length of each lug being greater than the flattened-out length of the skirt portion.

3. A closure cap comprising a cover portion and a skirt portion, the edge of the skirt portion being rolled into a bead, sealing means in said closure cap, elongated lugs extending inwardly from said skirt and integral with said bead the flattened-out length of each lug being greater than the flattened-out length of the skirt.

4. A non-circular closure cap comprising a cover portion and a skirt portion, the edge of the skirt portion being rolled into a bead, sealing means in said closure cap, elongated lugs extending inwardly from said skirt and integral with said bead, the flattened-out length of each lug being greater than the flattened-out length of the skirt.

5. The method of forming a closure cap which comprises the steps of making a blank having a plurality of apexes and side edges connecting said apexes, drawing areas of said blank adjacent said edges and apexes to form a cup-shaped shell with a skirt having short and long sections, coaxing the edges of said long sections of said skirt inwardly and thereafter turning said short and

long sections inwardly simultaneously to form a bead and holding lugs integral with said bead.

6. The method of forming a closure cap which comprises the steps of making a blank having a plurality of arcs at its edge, drawing said blank along chords facing said arcs to form a shell with a skirt portion having long and short sections, turning said long section of the skirt portion inwardly to form holding lugs and turning the short sections inwardly to form a bead.

7. A closure cap comprising a cover portion and a 10 skirt portion, the edge of the skirt portion being rolled inwardly to form a bead, elongated lugs extending inwardly from said skirt portion and integral with said bead and overlying a substantial portion of the inner surface of

5 the skirt, a liner within said cap and having its edges intermediate said cover portion and said lugs, the lower edge of the bead and of said lugs being on substantially the same plane, and the flattened out length of each lug being greater than the flattened out length of said skirt portion.
